US0D1053687S

(12) **United States Design Patent** (10) **Patent No.:** **US D1,053,687 S**
(45) **Date of Patent:** **** Dec. 10, 2024**

(54) **PLIERS**

(71) Applicant: **Milwaukee Electric Tool Corporation**,
Brookfield, WI (US)

(72) Inventor: **Adam M. Moller**, Waukesha, WI (US)

(73) Assignee: **Milwaukee Electric Tool Corporation**,
Brookfield, WI (US)

(**) Term: **15 Years**

(21) Appl. No.: **29/836,734**

(22) Filed: **Apr. 28, 2022**

(51) **LOC (14) Cl.** **08-05**

(52) **U.S. Cl.**

USPC **D8/52**

(58) **Field of Classification Search**

USPC D8/4, 5, 14, 51–60, 105, 107

CPC B26B 17/00; B26B 7/02

See application file for complete search history.

(57) **CLAIM**

The ornamental design for a pliers as shown and described.

DESCRIPTION

FIG. 1 is a perspective view from the right side of an embodiment of the claimed design;

FIG. 2 is a perspective view from the left side of the claimed design of FIG. 1;

FIG. 3 is a right side view of the claimed design of FIG. 1;

FIG. 4 is a left side view of the claimed design of FIG. 1;

FIG. 5 is a top view of the claimed design of FIG. 1;

FIG. 6 is a bottom view of the claimed design of FIG. 1;

FIG. 7 is a front view of the claimed design of FIG. 1;

FIG. 8 is a rear view of the claimed design of FIG. 1;

FIG. 9 is a perspective view from the right side of an embodiment of the claimed design;

FIG. 10 is a perspective view from the left side of the claimed design of FIG. 9;

FIG. 11 is a right side view of the claimed design of FIG. 9;

FIG. 12 is a left side view of the claimed design of FIG. 9;

FIG. 13 is a top view of the claimed design of FIG. 9;

FIG. 14 is a bottom view of the claimed design of FIG. 9;

FIG. 15 is a front view of the claimed design of FIG. 9;

FIG. 16 is a rear view of the claimed design of FIG. 9.

The ornamental design which is claimed is shown in solid lines in the drawings: The broken lines in the drawings are for illustrative purposes only and form no part of the claimed design. The broken dot-dash lines define boundaries of the claimed design and form no part thereof.

1 Claim, 14 Drawing Sheets
